US00D535951S

(12) **United States Design Patent** (10) **Patent No.:** **US D535,951 S**
Fort et al. (45) **Date of Patent:** **** Jan. 30, 2007**

(54) **PORTION OF A DIMMER CONTROL SWITCH AND COVER PLATE**

(75) Inventors: **Tucker H. Fort**, New York, NY (US); **Mark B. Greenwald**, Westport, CT (US); **Jean Claude Marcou**, Limoges (FR); **Jay J. Mendelson**, Hartsdale, NY (US)

(73) Assignee: **Cooper Wiring Devices, Inc.**, Peachtree City, GA (US)

(**) Term: **14 Years**

(21) Appl. No.: **29/243,094**

(22) Filed: **Nov. 18, 2005**

Related U.S. Application Data

(60) Continuation of application No. 29/221,627, filed on Jan. 19, 2005, now Pat. No. Des. 511,751, which is a division of application No. 29/193,479, filed on Nov. 10, 2003, now Pat. No. Des. 504,668.

(57) **CLAIM**

The ornamental design for a portion of a dimmer control switch and cover plate, as shown and described.

DESCRIPTION

FIG. 1 is a front, bottom and right side perspective view of the design;

FIG. 2 is a front view thereof;

FIG. 3 is a right side view thereof;

FIG. 4 is a left side view thereof;

FIG. 5 is a top plan view thereof; and,

FIG. 6 is a bottom plan view thereof.

The rear is not part of the claimed design. The broken line showing in the drawings is illustrative and forms no part of the claimed design.

1 Claim, 3 Drawing Sheets
